UNITED STATES PATENT OFFICE.

EDWARD A. CHARBONNEAUX, OF SAN FRANCISCO, CALIFORNIA.

FUEL AND PROCESS OF PRODUCTION.

No Drawing.

Application filed December 20, 1920. Serial No. 432,043.

To all whom it may concern:

Be it known that I, EDWARD A. CHARBONNEAUX, a citizen of the French Republic, residing at San Francisco, in the county of San Francisco and State of California, have invented new and useful Improvements in Fuel and Processes of Production, of which the following is a specification.

This invention relates to composition of matter, and particularly pertains to liquid fuels.

Due to the present shortage and probably future scarcity of petroleum as a source of heavy fuels for oil burning apparatus and light oils for internal combustion engines, it has been found desirable to provide a liquid fuel substitute, readily adapted to displace heavy or light hydrocarbons. With this idea in view, it is the principal object of the present invention to provide means for enriching easily obtained liquid hydrocarbons, such as alcohol, and thereby rendering them suitable as substitutes for mineral hydrocarbons of the petroleum group.

The present invention contemplates the use of crude or raw alcohol derived from any source, and to which liquid or solid soluble hydrocarbons are added, to produce a desirable, freely burning, smokeless hydrocarbon fuel.

At the present time alcohol may be obtained from many sources in inexhaustible quantities. This liquid alone is too lean, too light, and lacking of elasticity, however, for practical use, as a fuel, and in the present instance, a soluble liquid or solid hydrocarbon is produced by a process hereinafter to be described, and is added to the alcohol to raise its carbon content, to increase its elasticity and power. The soluble solid or liquid hydrocarbon may be obtained from many sources, as for example: petroleum of any gravity, hydrocarbon oils of vegetable derivation used in a liquid or solid or concrete state, that is to say, including the rosins and gum rosins. This soluble hydrocarbon is recovered from oils or gum rosins in the form of a thick, sticky, dense, viscous liquid, or spongy dry matter, according to the material used in the production. This is done by nitrification, for example, by adding five, ten or more parts of concentrated nitric acid to one hundred parts of petroleum crude oil containing nitratable ingredients, such

as the California petroleum oils. The mixture is put over a gentle fire and stirred. It boils emitting red fumes. The end of the reaction is indicated when the red fumes cease. When the mixture is cooled it will be noticed that the oil of petroleum which was homogenous before the beginning of the action has now been broken up and separates in a number of different layers. The 60 lightest one is white or pale yellow, is composed of the oils of vaseline and paraffin and is insoluble in nitric acid and alcohol. Another one is a heavy tarry substance insoluble in nitric acid and alcohol. Another 70 layer is a brown sticky substance soluble in alcohol but insoluble in nitric acid. It is this substance which is the object of the present application and which may be called a soluble extract of petroleum or nitrated 75 extract of petroleum or a nitrated colloidal substance which is a product of the treatment of certain petroleum oils with nitric acid. The same process is applied to the hydrocarbon oils of vegetable derivation, 80 and also to powdered gum rosins for the purpose of obtaining a soluble liquid or solid hydrocarbon thoroughly oxidized. The only difference when dealing with such various products is to eliminate the use of 85 heat when the hydrocarbons are vegetable, as the oxidization of vegetable hydrocarbons is rapidly brought about by nitric acid without heat. Heat is, however, desirable when working with mineral hydrocarbons, as 90 they are not so readily oxidized as the vegetable ones, thus requiring that the mixture be gently heated as the oxidization proceeds. The reaction is indicated by the emission of 95 red, nitrous acid fumes and an elevation of temperature. When the nitrification is completed, it will be noted that the liquid resolves itself into three strata, the upper one being an oily substance, consisting of 100 a mineral hydrocarbon oil, containing some oxidized carbon. The central layer is of different shades, its upper part being clear brown, while its lower part is darker. This central stratum is the soluble hydrocarbon substance, with which the present invention 105 is particularly concerned. It is a viscous semi-liquid substance containing a portion readily soluble in alcohol, and a certain proportion of bituminous substance, which forms a sediment in the alcoholic solution, 110 and may be separated therefrom by straining or decantation. The lowermost layer

consists of the exhausted nitric acid used in the process, and which acid may be partly regenerated and recuperated if desired. A still heavier layer is evolved when very dense hydrocarbon mineral oils are used, such layer being of a tarry nature.

It will be readily recognized that the light upper layer may be used as a mineral hydrocarbon oil for various purposes, while being susceptible to further nitrification, to yield a proportion of soluble hydrocarbon. The lower layer might also be of commercial value, while that part of the acid used in the process may be saved, thus providing by-products, which would in themselves afford a considerable revenue, in addition to that obtained by the soluble hydrocarbon, which is to be mixed with alcohol.

It is well known that petroleum is not soluble in alcohol, due to its peculiar content of mineral oil. The nitrification of the petroleum will eliminate objectionable mineral matter, as well as other heavy products, at the same time bringing about oxidation.

25 This will insure that when the alcohol and the soluble hydrocarbon substance have formed a fuel, combustion will take place at a high temperature, and with a flame free from unburned carbon.

30 It will also be understood that during the process of producing the soluble hydrocarbon, apparatus may be provided for the recovery of the nitrous acid fumes. In the instance of nitrifying hydrocarbon oils, liquids or solids of vegetable derivation an adequate apparatus would permit the recovery of valuable by-products, consisting in volatile oils of the aromatic group, as: terebene, terpinol, and the like, according 40 to the material used.

By this process, it is thus possible to obtain a large number of by-products and different kinds of fuels, liquids and gas. One of the liquids may be used for heating purposes and is made by the simple solution of desired proportions of the soluble hydrocarbon in alcohol, as for example: alcohol, one hundred parts, soluble hydrocarbon, preferably one to three parts, and in some 50 instances the solution might be a saturated one. In burning this fuel the liquid may be made to escape from a nozzle, through which it is forced by pressure, while the vapors are continuously ignited by a small 55 pilot light. This will insure that the atomized fuel will burn without smoke or residue.

Another liquid fuel may be produced in the same manner previously described, with 60 the addition of a volatile, combustible liquid, such as an ether, or other extremely light hydrocarbon. By this mixture an explosive fuel is obtained. A general formula

for such a fuel would be: alcohol, one hundred parts, soluble hydrocarbon, one 65 to three parts, and twenty parts of an ether, (sulphuric, amylic, oenanic, acetic, nitric, amylacetate, acetone, and the like). Such a fuel may be readily carbureted to produce a gas for explosive engines.

It will thus be seen that by treating mineral and vegetable liquid or concrete hydrocarbons, by nitrification, a desirable oxidized soluble hydrocarbon will be obtained for use in enriching alcohols, and that in addition, a gaseous fuel and numerous valuable by-products may be recovered, rendering the process commercially profitable, and at the same time providing means for utilizing alcohol as a fuel, which liquid may be obtained in large quantities, and which, when enriched by the soluble hydrocarbon, will produce fuel substitute for heavy heating fuels, as well as the lighter volatile fuels, thus sparing the questionable stock 85 of petroleum and providing for an adequate fuel.

While I have shown the preferred form of my invention as now known to me, and have disclosed a preferable embodiment 90 thereof, both as to the constituents and the process of treating the same, it is to be understood that various changes in the ingredients and their proportions might be made, without departing from the spirit 95 of the invention, as claimed.

Having thus described my invention, what I claim and desire to secure by Letters Patent, is:

1. A method of making a liquid fuel comprising treating crude oil containing nitratable ingredients with nitric acid, separating the nitrated product and mixing it with suitable proportions of alcohol.

2. A liquid fuel consisting principally of 105 alcohol and containing the oxidized products resulting from the nitration of crude oil.

3. A liquid fuel consisting of 100 parts of alcohol, to which is added from 1 to 3 parts of the oxidized products resulting from the nitration of crude oil.

4. A liquid fuel consisting of 100 parts of alcohol and 20 parts of ether, to which is added from 1 to 3 parts of the oxidized 115 products resulting from the nitration of crude oil.

5. The process of producing a hydrocarbon compound soluble in alcohol by treating crude petroleum with nitric acid, which 120 process leaves the paraffin hydrocarbons and inert bituminous material untouched and produces an oxidized or nitrified mixture of hydrocarbons.

EDWARD A. CHARBONNEAUX.
